Attorney

UNITED STATES PATENT OFFICE.

THOMAS W. CONNOLLY, OF LOS ANGELES, CALIFORNIA.

ADJUSTABLE SUPPORT.

Application filed August 16, 1924. Serial No. 732,498.

To all whom it may concern:

Be it known that I, THOMAS W. CONNOLLY, a citizen of the United States, and a resident of Los Angeles, in the county of 5 Los Angeles and State of California, have invented certain new and useful Improvements in Adjustable Supports, of which the following is a specification.

My invention relates to adjustable supports, and a purpose of my invention is the provision of an adjustable support of extremely simple, inexpensive, and durable construction which is particularly applicable to adjustable chair backs, but which 15 may be used in any other connections where an adjustable support is necessary.

It is also a purpose of my invention to provide an adjustable support including a supporting member adapted for pivotal 20 connection to the chair back, and a locking member pivoted on the chair frame so as to normally gravitate to one position in which the supporting member is locked against movement to prevent lowering of 25 the chair back, and which is movable by the supporting member to another position in which the supporting member is freely movable to permit lowering of the chair back.

I will describe only one form of adjustable 30 support embodying my invention and one adaptation thereof, and will then point out the novel features thereof in claims.

In the accompanying drawings:

Figure 1 is a view showing one form of 35 adjustable support embodying my invention in applied position with respect to a chair back;

Figure 2 is an enlarged fragmentary sectional view of the chair, with the adjustable 40 support in back supporting position;

Figure 3 is a view similar to Figure 2, showing the chair back in completely lowered position;

Figure 4 is a vertical sectional view taken 45 on the line 4-4 of Figure 2.

Referring specifically to the drawings, in which similar reference characters refer to similar parts in each of the views, my invention in its present embodiment comprises a stationary element 15 which, in the 50 present instance, is a part of the chair frame, and a pivoted element 16 comprising the chair back, it being noted that the element is pivoted on the stationary element 55 by means of hinges 17 whereby the back is

capable of being adjusted to various inclinations.

In the present instance I have shown two stationary elements 15 and two adjustable supports associated with the stationary elements. As the two supports are identical in construction a description of one will suffice for all.

As shown in Figure 2, the stationary element 15 is formed with an opening 18, and within this opening is mounted a locking member including a stationary plate 19 secured to one wall of the opening and a movable plate 20 pivoted on the stationary plate and provided with an opening 21 through 70 which a supporting member or connecting rod 22 is adapted to slide. The upper end of the supporting member is pivotally connected at the point indicated at 23 to the plate 24 secured to the pivoted element or chair back 16, and this supporting member is threaded at its opposite ends to accommodate nuts 25 and 26 which constitute lugs or abutments, the purpose of which will be hereinafter described.

A spring latch 26 is secured to the plate 19 of the locking member, and this latch is curved to provide a bill 27 arranged to receive and secure the movable plate 20 in the dotted line position shown in Figure 2.

In operation, the plate 20 of the locking member normally gravitates to the inclined position shown in Figure 2, wherein the wall of the opening 21 has binding engagement with the supporting member 22 when the pivoted member 16 is in inclined position as shown, so as to exert a downward pressure upon the supporting member. Through this binding engagement the supporting member is locked against downward movement so as to firmly retain the seat back in inclined position. However, the supporting member can be moved upwardly through the opening of the plate to effect any desired elevation or adjustment 100 of the seat back, but as soon as the seat back is released so that its own weight can again be exerted upon the supporting member, the plate 20 will again function to bite the supporting member and thus lock the latter 105 against downward movement.

The supporting member 22 is capable of occupying an extreme elevated position as shown in dot and dash lines in Figure 2, or an extreme lowered position as shown in 110

solid lines in Figure 3. In the extreme elevated position, the nut 26 elevates the plate 20 so that the latter is engaged by the bill 27 of the latch 26, and in this position of the plate 20 it is disposed at right angles to the supporting member or rod 22 so that the wall of the opening 21 will be ineffective to engage the rod and lock the latter against downward movement whereby the rod can be moved downwardly to permit a lowering of the chair back 16. In the lower extreme position as shown in Figure 3, the nut 25 engages the plate 20, thus forcing the latter downwardly away from the bill 27 so that the plate can gravitate to its normal position wherein it operates as a locking means for the rod 22, as has been previously described.

Although I have herein shown and described only one form of adjustable support embodying my invention, it is to be understood that various changes and modifications may be made herein without departing from the spirit of the invention and the spirit and scope of the appended claims.

What I claim is:

1. An adjustable support comprising a supporting member adapted for pivoted connection to a pivotal element, and a locking member adapted to be pivoted on a stationary element to normally gravitate to one position in which the supporting member is locked against movement to prevent lowering of the pivotal element and which is movable by the supporting member to another position in which the supporting member is freely movable to permit lowering of the pivotal element, and a latch associated with the locking member to secure the latter in the second mentioned position and thus allow lowering of the pivotal element, and abutments on the supporting member, one of which is adapted to engage the locking member as the supporting member reaches its uppermost position and move the locking member into engagement with the latch, and the other of which is adapted to engage the locking member when the supporting member reaches its lowermost position and move

the locking member out of engagement with the latch.

2. An adjustable support comprising a pivoted rod, a locking member including a stationary plate and a movable plate provided with an opening receiving the rod, said plate normally occupying a position in which the rod is freely movable through the opening in one direction and which is locked against movement in the other direction, a latch for securing the movable plate in a position in which the rod is freely movable through the opening in both directions, and lugs on the rod, one of said lugs being adapted to engage the movable plate to force the latter out of engagement with the latch, and the other lug to engage the movable plate to lift the latter into engagement with the latch.

3. In a device of the class described, a hinged apertured plate adapted to be mounted upon a fixed object, a latch member in coaction with the plate to hold same at one time against hinged movement, and a rod slidable through the aperture of said plate and provided with means to respectively engage the plate and disengage same from said latch, the hinged plate functioning when disengaged from said latch to permit its aperture to be canted with respect to the rod and to hold the latter in its position of adjustment.

4. In a device of the class described, a swinging plate having an opening therein, a rod slidable through the opening in the plate and adapted to be angularly positioned with respect to the walls of the opening so as to be brought into locking contact therewith, and means to permit the plate to be held in one position so that said rod may be moved along a line representing the true longitudinal axis of the opening to thereby permit the rod to slide freely and to be held out of locking contact with the walls of said opening including a spring latch engageable with the plate, and portions on the rod for respectively engaging the plate with and disengaging the same from said latch.

THOMAS W. CONNOLLY.
